CLAIM

The ornamental design for an ammunition magazine loader accessory, as shown and described.

DESCRIPTION

FIG. 1 is a top and front perspective view of an ammunition magazine loader accessory showing my new design.

FIG. 2 is a top plan view thereof.

FIG. 3 is a bottom view thereof, showing a recessed area that is not visible from the top.

FIG. 4 is a left side elevational view thereof.

FIG. 5 is a right side elevational view thereof.

FIG. 6 is a front end elevational view thereof; and,

FIG. 7 is a rear end elevational view thereof.
